DISPENSING DEVICE

Russell L. Sanderson, Spokane, Wash.

Application September 25, 1935, Serial No. 42,044

5 Claims. (Cl. 221—60)

This invention relates to an improved dispensing device and more particularly to a device adapted to be secured in a vertical position against a wall or other support and serve as means for housing a tube of tooth paste, shaving cream or the like and permit contents of the tube to be discharged therefrom when needed.

One object of the invention is to so construct a container or housing constituting the body portion of the dispensing device that a collapsible tube may be easily inserted through the upper end thereof and supported in a vertical position in the housing with its discharge neck secured through a passage in the bottom of the housing whereby tooth paste or the like may be discharged from the tube on to a brush placed under the device when pressure is applied to the tube.

Another object of the invention is to provide improved means for engaging the neck of the tube which may be either threaded or unthreaded and firmly but releasably secure the neck in position through the passage formed through the bottom of the housing.

Another object of the invention is to so form the housing that a winding key for rolling and compressing the tube may project externally of the housing through a slot formed longitudinally therein and thus allow the key to be turned to expel contents of the tube without removing the cover of the housing.

Another object of the invention is the provision of improved means for closing the lower end of the discharge neck of the tube when not in use, the closure being so mounted that it can be very easily moved to a closed or opened position and when closed prevented from accidentally moving to an opened position.

The invention is illustrated in the accompanying drawing wherein,

Fig. 1 is a side elevation of the improved dispensing device,

Fig. 2 is sectional view upon an enlarged scale taken vertically through the dispensing device,

Fig. 3 is a perspective view illustrating the manner in which the neck of the tube is gripped, and

Fig. 4 is a section taken along the line 4—4 of Figure 1.

This improved dispensing device has a hollow body formed of metal or other desired material and constituting a container or housing 1 in which the collapsible tube 2 is mounted in a vertical position as shown in Figures 1 and 2. A removable cover 3 is provided for the open upper end 5 of the container and at its lower end the container is formed with a bottom 4 through the center of which is formed a large opening 5. By providing an oversized opening in the bottom of the housing or container the housing will accommodate tubes having discharge necks of various

diameters. In the present illustration the neck 6 is externally threaded but it is to be understood that the neck need not be threaded in order to allow the tube to be supported within the housing. Brackets 7 are secured to the housing adjacent the upper and lower ends thereof and project from the housing to such an extent that securing screws may be easily passed through the brackets to mount the housing against a wall or other support in a vertical position.

Contents of the tube are to be discharged therefrom through the neck 6 and in order to do so there has been provided a key 9 formed of strong metal and of such length that when it is disposed transversely in the housing with the upper end of the tube engaged through the slot 10 of the key, the end portion of the key carrying the turning head 11 will project outwardly through the slot 12 formed longitudinally of the housing at one side thereof. Therefore, by grasping the head or finger piece 11 the key may be easily turned to wind the tube upon the key and expel contents of the tube through the neck. As the slot is open at its upper end the key may be applied to a tube and the tube and key then moved downwardly into the housing with the key extending through the slot and when the tube reaches the bottom of the housing the neck will pass through the opening 5.

A metal disk or washer 13 is welded or otherwise fixed to the bottom of the housing with its opening 14 registering with the opening 5 and by referring to Figures 3 and 4 it will be seen that upper face of the disk is recessed as shown at 15 to provide a pocket in which a latch 16 is pivotally mounted by a pin 17. This latch is substantially V-shaped and has a bill 18 and an actuating arm or lever 19, the lever being bent longitudinally to provide a depending flange 20 which limits inward movement of the latch beyond the position shown in Figures 3 and 4 and has its free end portion extended and bent to provide a tongue 20'. The tongue projects from the side edge face of the disk when the latch is moved inwardly into position for the free end of the bill to bear against and grip the neck 6 of the tube and therefore the latch can be easily engaged by a finger and swung outwardly to a releasing position. A portion of the disk is undercut at the opposite side of the opening 14 from the pocket 15 to provide a lip 21 adapted to have interlocking engagement with threads of the neck and the free end of the bill 18 of the latch is serrated as shown in Figure 2 to provide teeth 22 of the proper size for engaging threads of the neck. Therefore, when the neck is extending through the passage formed by the registering openings 5 and 14 and the latch swung inwardly to its operative or securing position, threads of the neck will be engaged by the lip 21 and teeth 22 and the tube will be firmly

supported in a vertical position and prevented from moving out of the position shown in Figure 2. If the neck is unthreaded, the lip 21 and teeth 22 will bite into the neck and thus firmly grip the neck and maintain the tube in the upright position. It will thus be seen that a tube having either a threaded or unthreaded neck can be firmly gripped and supported in an upright position in the housing. When contents of the tube 10 have all been used it is merely necessary to swing the latch outwardly to a releasing position and after removing the cap 3 slide the key upwardly through the slot until the key, with the tube wound thereon, is moved upwardly out of the 15 housing. The used tube can then be removed from the key, a new tube applied and the tube and key moved into place within the housing.

It is desired to prevent drying of the contents of the tube when not in use while at the same 20 time allowing easy dispensing thereof, and in order to do so there has been provided a cap 23 fixed upon the upper face of an arm or lever 24 which extends under the housing radially thereof with one end pivoted to hinge ears 25 depending from the bottom of the housing. The lever 25 is formed of resilient metal and has its free end portion bent upwardly as shown at 26 and terminating in a latch 27 for engaging a tooth or keeper 28 carried by the housing at the front 30 thereof. A portion of the latch projects outwardly from the housing to provide a finger engaging element 29 and by referring to Figure 1 it will be seen that by applying pressure to the finger engaging element the arm or lever can be easily released and will then drop to a depending position in which it will be out of the way and not interfere with placing of a tooth brush or shaving brush under the open neck 6 of the tube. After a desired quantity of tooth paste or shaving cream 40 has been expelled by turning the key 9 the arm 24 can be swung upwardly to a raised position and when pressure is applied thereto to move the latch 27 into engagement with the keeper 28 the arm will be held in place with the cap 23 about 45 the exposed lower portion of the neck 6. Therefore, the neck will be shielded by the cap and contents of the tube prevented from drying or becoming rancid by exposure to air.

I have, therefore, provided a dispensing device 50 in which a tube of tooth paste or shaving cream may be mounted for use and contents thereof easily dispensed.

Having thus described the invention, what is claimed as new is:

55 1. In a dispensing device of the character described, a receptacle slotted longitudinally and open at its top and having its bottom formed with an opening, a washer fixed to the bottom and formed with an opening aligned with the opening 60 of the bottom and with a recess in its upper face defining a pocket leading from a side of said aligned openings, a lip being provided at the other side of the opening of the washer, said receptacle being adapted to receive a collapsible tube having an externally threaded neck of a diameter to be passed through the aligned openings, a latch pivotally mounted in said pocket and having a bill projecting into the aligned openings and a handle disposed externally of the washer for turning the latch about its pivot and moving the bill into engagement with the threaded neck of the tube to bind the neck in engagement with said lip, a key extending through the slot of the receptacle and having its portion within the recep-

tacle slotted for engagement about the upper end of the tube to wind the tube about the key and expel contents of the tube through the neck when the key is turned, an arm pivotally mounted under said receptacle, a cap for said neck carried by said arm, and means for releasably holding the arm in a raised position with the cap in closing relation to the neck. 5

2. In a dispensing device, a housing having a bottom formed with an opening and adapted to receive a tube with a neck thereof extending through the opening, a washer fixed to the bottom of the housing with its opening registering with the opening of the bottom, said washer having a recess leading from its opening, and a latch 10 pivotally mounted in the recess and having an actuating arm and a bill for moving across the opening of the washer when the latch is moved to an operative position, the portion of the washer at the opposite side of its opening from the recess 15 being formed with a lip to cooperate with the bill and grip the neck of the tube when the latch is in its operative position.

3. In a dispensing device, a housing adapted to receive a tube and having a passage at its bottom 20 to receive the discharge neck of the tube, a member projecting downwardly from the bottom of the housing about said passage and formed with a pocket leading from a side of the passage, a lip carried by said member at the opposite side of the 25 passage from said pocket, and a latch movably mounted in said pocket and having a portion movable into and out of a position across the passage and when projected across the passage adapted to engage the neck of the tube whereby 30 the neck will be gripped between the latch and lip and the tube held upright with its neck extending through the passage.

4. In a dispensing device, a housing adapted to receive a tube and having a passage at its bottom 40 to receive the discharge neck of the tube, a member projecting downwardly from the bottom of said housing about said passage and formed with a lateral pocket leading from said passage, a lip carried by said member at the opposite side of the 45 passage from said pocket, a gripper pivoted in said pocket and having an actuating lever projecting externally from the pocket, and a bill projecting into one side of the passage and terminating in a toothed end for engaging the neck 50 of the tube and binding the neck against said lip to support the tube in an upright position in the housing.

5. In a dispensing device, a housing adapted to receive a tube and having a passage at its bottom 55 to receive the discharge neck of the tube, means to secure the neck in the passage and support the tube vertically in the housing with its neck projecting outwardly from the passage, a keeper at the front of the housing adjacent the 60 lower end thereof, a strip of resilient material pivoted to the bottom of the housing at a point diametrically opposite the keeper and extending diametrically of the bottom and having its free end portion bent upwardly to form a latch for engaging the keeper and then outwardly to form a finger engaging element projecting forwardly from the housing, and a cap carried by said strip and projecting upwardly therefrom and disposed about 65 the outer end of the neck to close the neck when the strip is swung upwardly and secured in a raised position diametrically of the housing. 70
